UNITED STATES PATENT OFFICE.

RELZEMAN R. NANCE, OF FREDERICK, OKLAHOMA.

FRAMING-GUIDE.

1,295,788.

Specification of Letters Patent. Patented Feb. 25, 1919.

Application filed August 25, 1917. Serial No. 188,168.

To all whom it may concern:

Be it known that I, RELZEMAN R. NANCE, a citizen of the United States, residing at Frederick, in the county of Tillman and 5 State of Oklahoma, have invented certain new and useful Improvements in Framing-Guides, of which the following is a specification.

This invention relates to framing guides, 10 and particularly to a guide structure adapted for use with an ordinary steel square such as is now commonly used by carpenters, and others, and which guide is designed particularly for use in planning and 15 cutting a frame work, or brace framing, in laying off a stair, measuring and finding cuts for braces, forming polygons, cutting miters, and the like.

An object of the invention is to provide 20 a guide bar which has indicating markings thereon and which is adapted to have the steel square fitted thereto and adjusted to various settings, to thus provide a guide of such character that when the square is laid 25 upon the timber or piece of lumber to be cut, it will be presented in the proper relation for use and will be positively held to give the proper angle.

A further object lies in providing means 30 by which the square can be positively clamped to lock in the set relation with respect to the guide bar, which clamping means is so constructed that immediately this clamping pressure is released, the parts will be 35 moved from bearing engagement upon the tongue and blade of the square, thus making it possible to quickly and easily adjust the same for the different uses as stated above.

Yet another object resides in providing 40 scales upon the guide bar in clear and concise form so that by following instructions an ordinary mechanic, not highly skilled in the use of figures or in calculations usually required in framing, can with the greatest 45 facility properly obtain the length of and mark off seat and plumb cuts of roof framing and bracing timbers for use upon common rafters, hip rafters, octagonal hip rafters, and the like, and which may with equal 50 accuracy be used in laying off a stair, or in marking off and laying out polygonal forms and framing structures.

With the above and other objects in view, 55 which will be in part described and in part understood from the specification, drawings, and claims, my invention consists in certain

novel features of construction and combinations of parts which will be hereinafter more fully set forth.

In the drawings:

Figure 1 is a view in plan showing the guide bar with a square fitted thereon and illustrating the manner of using the same;

Fig. 2 is a bottom plan view of the disclosure in Fig. 1;

Fig. 3 is a sectional view taken on the line 3—3 of Fig. 1;

Fig. 4 is an enlarged detail view of the guide bar and intended to better show the manner of giving the indicated scales;

Fig. 5 is a transverse sectional view on the line 5—5 of Fig. 4;

Fig. 6 is a fragmentary view to better disclose the arrangement of the slide block by which one of the square clamping means is carried;

Fig. 7 is a sectional view taken on the line 7—7 of Fig. 4;

Fig. 8 is a perspective view to better disclose the form of the slide block;

Fig. 9 is a sectional view on the line 9—9 of Fig. 7, and looking in the direction indicated by the arrow; and,

Fig. 10 is an enlarged sectional view on the line 10—10 of Fig. 9 with the clamp screw omitted.

The guide bar 1, which is wood, metal, or other suitable material, has the edge 2 thereof formed as a straight-edge, and this bar has an elongated slot 3 formed transversely therethrough and extending from adjacent one end of the bar, in a parallel line with respect to the straight-edge 2, and from near the right end to substantially the middle of the bar.

The material of the guide bar 1 is cut away on the rear face so that a guide track is formed as shown at 4, and a substantially T-shaped slide block 5 is formed to be received in this track with the central rib thereof extending through the slot 3 and having its upper face substantially flush with the face of the bar 1. A boss 6 is provided on the upper face of the central rib, and a bore 7 is formed through this boss and the slide block 5. A clamping button 8, the structure of which is better shown in Fig. 10, has a bore 9 therethrough lined up with the bore 7 of the slide block 5, and the bore is enlarged on the lower side of this button, so that the boss 6 of the block 5 will have a loose fit therein. A clamp bolt 11 is passed

through the bore 7 of the block 5 and the boss 6, and through the bore 9, of the clamp button 8, and a thumb nut 12 is fitted on the screw-threaded end thereof to be tightened down against the button 8. Within the enlarged portion 10 of the bore, an intermediate bore 13 is provided, it being understood that the bore 9 which conforms substantially to the diameter of the clamp bolt 11 is still maintained at the top of the button 8, and on its lower face this button 8 is beveled at one side so that a fulcrum point 14 is provided. As the clamp bolt 11 is fitted in place and the thumb nut 12 is tightened down, it will of course be appreciated that the clamping button 8 will be rocked on the point 14 as a fulcrum, due to the fact that this point will bear upon the face of the bar 1 adjacent the slot 3 thereof, and at the same time the head portion of the slide block 5 will be clamped within the track 4 formed in conjunction with the slot 3. As has been stated, the button 8 is cut away at one side on the lower face, and this clearance is sufficient so that the blade or body of an ordinary steel square can be fitted therebeneath, and as the thumb nut is tightened down, the rocking of this button 8 on the fulcrum point 14 will cause the same to bear down and clamp against the blade or body of the square, the slide block 5 and consequently the button 8 being locked in rigid setting with respect to the guide bar 1 in the manner set forth. As it is the intention that the square shall be readily adjustable when the thumb nut 12 is loosened, it is preferable that a coiled spring be mounted around the clamp bolt 11 within the bore 13, this spring being indicated by the reference numeral 15, in Fig. 5. The spring 15 bears at one end upon the boss 6, and at its other end against the shoulder at the head of the bore 13, and thus as the thumb nut 12 is loosened upon the clamp bolt 11, the clamp button 8 will be moved and swung upwardly on its fulcrum point 14 and the reduced edge of this button will be raised from its clamping and frictional bearing engagement with the blade or body of the square.

As has been stated, the slot 3 is formed preferably entirely within one end of the bar 1, although of course this slot might be given greater length than above specified. As it is desired to also set and secure the tongue of the steel square, when the device is to be used in measuring and marking timbers and the like, openings 16 are provided transversely through the guide bar 1 adjacent the other end thereof, a clamp bolt 17 being fitted through one of these openings with its screw-threaded end extended above the top face of the bar. A clamping button 18, which is very similar to the button 8 but which need not have the

enlarged bore 10 is fitted over the threaded end of the clamp bolt to have the fulcrum point thereof bear upon the upper surface of the bar. As is the case with the button 8, this clamp button 18 is cut away at one side 70 for reception of the steel square, and a coiled spring 19 is fitted around the clamp bolt 17 to be received within the bore of the button 18, and to bear upwardly against the shoulder of the top of this bore to normally exert force to raise the button 18 from clamping engagement with the tongue of the square as the same is fitted within the cut out or reduced portion of the button. A thumb nut 20 is provided to be fitted on the threaded end of the clamp bolt 17 to be turned down to rock this button 18 around its fulcrum point and move the same against the force of the spring 19, to accomplish clamping pressure upon the tongue of a 80 steel square. By providing the clamp buttons 18 and 8, the latter of which is movable through the sliding mounting of the block 5, it is possible to so adjust the clamping parts that a steel square can be set upon the guide bar 1 to have any desired angle drawn along the edges of the tongue and the blade and through the straight-edge 2 of the bar 1.

The face of the guide is inscribed near its left end with a mark 21 crossing the straight edge 2 and a mark 22 crossing the opposite edge. The face of the guide is also inscribed near its right portion, and along that part which is slotted, with a series of scales (see Fig. 4) whose markings are at right angles to and cross the straight edge 2 and whose figures adjacent said markings give various information with relation to legends on the face opposite the respective lines of said scale. That is to say, as shown in the drawings, the second line of the scale gives the pitch, or rather the various pitches of the rafters being cut. By preference the uppermost lines of the scale contains figures to coact with the respect graduations of the blade of an ordinary steel square, which blade is marked as usual with figures. The third line gives the length per one foot run and plumb cut of the common rafter. The next 105 is the same on a hip rafter, and the next the same on an octagon rafter. Adjacent the mark 21 are legends as shown. The mark 22 at the lower edge of the bar is for framing polygons, and at such times the graduations 12 on the tongue of the square will intersect the mark 22. The scale near the lower edge of the guide is shown in Fig. 4 as having but two rows, the first being the number of sides of the polygons and the second the 110 figures to coact with graduations on the blade of the square when the latter is reversed or turned with its angle downward instead of upward as shown in Fig. 1. At this time, the markings of the lowermost scale must ac- 130

curately intersect with the graduations on the blade, while the appropriate graduations on the tongue must accurately intersect the mark 22. Similarly, when the square is used 5 with its angle upright, as shown in Fig. 1, the graduations must intersect the proper markings on the upper scale and at the point 21. The buttons described above are for holding the two arms of the square after it

10 has been laid across the bar and adjusted to the proper point. The right hand button may obviously be adjusted within its slot. When the tongue of the square extends at a considerable angle to the bar, it may be 15 necessary to adjust the bolt or screw 17 into the other hole 16 near the left end of the bar, and this explains the use of a plurality of holes at this point.

In the use of this framing guide, the frame 20 or timber to be marked is laid across the straight edge 2 as shown in Fig. 1, and an ordinary steel square is laid over the face of the bar 1 and clamped thereto by the buttons after it has been properly adjusted. It 25 will hardly be necessary to give the various angles which may be found, and an explanation of what may be the simplest will prove sufficient. Let it be assumed that it is desired to cut a common rafter of $\frac{1}{4}$ pitch or 6 30 inches rise per foot on a building which is ten feet wide. The legend at the left end of Fig. 4 directs the numeral 12 on the tongue of the square be set directly opposite the point 21. The operator finds the pitch $\frac{1}{4}$ in 35 the second line of the scale to the right end of the bar, and opposite thereto is the numeral 6. This indicates that the 6 inch point on the blade of the square must be set opposite to the markings of this scale. With the 40 square adjusted and the buttons set up tight, the plumb cut can be marked on the timber or work along the side of the blade of the square, and the seat cut along the side of the tongue of the square. The pitch of the rafter 45 is found along the second line of the scale. For a rafter having a five foot run, which would be the case in a building ten feet wide, it is necessary only for the operator to mark

the timber opposite the point 21 and again opposite the point where the blade crosses 50 the straight edge, then move the bar and square to a second position with the tongue crossing the last-named mark and make a second mark with the blade in its new position and thus step off five times along the 55 timber, and then mark for the plumb cut as above shown.

I claim:

1. A framing guide for use with a square, the same consisting of a bar having a straight 60 edge to abut the beam being worked, one face of the bar being inscribed near one end with a mark to coact with the proper graduation on the tongue of said square and near its other end with scales whose figures give various pitches and the respective graduations on the blade of said square which must be set in coactive relation to the scale marking in order that said blade will indicate the plumb 65 cut and said tongue the seat cut on the work 70 simultaneously.

2. A framing guide consisting of a bar having a straight edge and a plurality of openings near one end and a longitudinal slot near its other end, and two fastening devices for clamping a square to the face of said bar, one selectively engaging one of said openings and the other adjustably mounted in said slot; the bar near one end having a mark intersecting said straight edge opposite which a certain point on the tongue of the square is to be set, and the face of the bar along its slot having scales whose markings intersect the straight edge and whose figures indicate the pitch and the respective 85 point on the blade of the square to be set opposite thereto, whereby the blade will indicate the plumb cut and the tongue the seat cut of a rafter of the pitch selected.

In testimony whereof I affix my signature 90 in presence of two witnesses.

RELZEMAN R. NANCE.
